COOLING DEVICE FOR ELECTRIC DISCHARGE TUBES

Joannes Cornelis van Warmerdam, Eindhoven, Netherlands, assignor, by mesne assignments, to North American Philips Company, Inc., New York, N. Y., a corporation of Delaware

Application March 18, 1953, Serial No. 343,076

Claims priority, application Netherlands April 10, 1952

3 Claims. (Cl. 313—45)

This invention relates to a cooling device for cooling, by means of a gaseous cooling medium, the cylindrical anode of an electric discharge tube which comprises a plurality of radial, cooling fins, the cooling medium being supplied at one of the extremities of the fins and the fins externally being either united to form a closed envelope or surrounded thereby.

The amount of heat which may be dissipated in cooling devices of the above-mentioned kind is limited by the temperature loss in the cooling fins, so that a large radial length of the cooling fins has in most cases no use, and furthermore by the fact that the fins must not be too long in the axial direction, since otherwise near the extremities of the cooling fins at which the cooling medium blows out, heat can no longer be dissipated to the cooling medium due to its becoming warmer and warmer. The cooling device concerned is in most cases of comparatively high weight, which frequently constitutes a disadvantage.

The object of the invention is to provide an improvement of cooling devices of the above-mentioned kind, by which either the dissipation of heat in a cooler of determined size is improved, or the cooling fins in the axial direction may be of greater length.

According to the invention, in a cooling device for cooling, by means of a gaseous cooling medium, the cylindrical anode of an electric discharge tube which comprises radial cooling fins, in which device the cooling medium is supplied at one of the extremities of the fins and the fins are externally either united to form a closed envelope or surrounded thereby, the cooling medium is supplied not only at one of the extremities of the fins but also at one or more places distributed over the length of the fins in such manner that the flows of cooling medium join. The cooling medium is preferably supplied through two co-axial tubes, of which the inner tube is provided with apertures and either constitutes the outer envelope of the cooling fins or is connected thereto. In the latter case, said envelope is likewise provided with apertures.

If additional cooling air is supplied between the fins at only one place, the apertures are provided over half or two third parts of their length, reckoned from the beginning. The amount of secondary cooling air is in this case from 25% to 30% of the total amount.

The above-mentioned step ensures that at the area, at which the additional cooling medium is supplied, its temperature is decreased, whilst the speed and the turbulence are increased. Said three factors contribute to an increase of the coefficient of thermal transmission over the remaining portion of the cooling fins, so that in total a greater amount of heat is dissipated than if the full amount of cooling medium were supplied at the beginning of the fins, whilst the resistance of the cooler is not increased.

In order that the invention may be more readily carried into effect, it will now be described with reference to the accompanying drawing, showing, by way of example, in axial section an air-cooling device having a dis-

2

charge tube arranged therein, as shown in Fig. 1, whereas Fig. 2 gives a bottom view of the device.

In the figures, reference numeral 1 indicates the glass upper part of a discharge tube which is shown broken off. 2 indicates the copper anode which is secured by means of soldering mass 3 in a cylinder 4, likewise of copper. The cylinder 4 comprises a flange 5, which is connected to the cooling conduits, and a plurality of cooling fins 6. The cooling flange 5 is connected to an outer tube 7 which contains an inner tube 8, said tubes jointly constituting the supply conduit for the cooling air. The cooling air substantially flows from above downwards between the cooling fins, but cooling air is also blown between the fins through apertures 9 and 10.

15 What I claim is:

1. In combination, an electric discharge tube having a cylindrical anode with a longitudinal axis, and a device for cooling said anode with a gaseous cooling medium; said device comprising a plurality of circumferentially-spaced radial cooling fins mounted on said anode, an envelope member having longitudinally-spaced apertures surrounding and secured to the edges of said fins, and means coaxing with said envelope member for introducing a cooling medium at one of the extremities of the fins and through the apertures in said member longitudinally spaced from said extremity to said fins, whereby the flows of the cooling medium join while passing along the fins in an axial direction thereby increasing the velocity of the cooling medium.
2. In combination, an electric discharge tube having a cylindrical anode with a longitudinal axis, and a device for cooling said anode with a gaseous cooling medium; said device comprising a plurality of longitudinally extending circumferentially spaced fins radially mounted on said anode, an inner tube having longitudinally spaced apertures in its wall and aligned with said axis and joined to and surrounding the edges of the fins, a solid outer tube concentric with and surrounding said inner tube and sealing off one end of said fins, and means associated with said tubes for introducing a cooling medium in the space between said tubes whereby the flow of cooling medium is through the apertures in said inner tube to the fins so that the flows join while passing axially along the fins and increase the velocity of the medium.
3. In combination; an electric discharge tube having a substantially cylindrical anode with a longitudinal axis, a plurality of longitudinally-extending circumferentially-spaced fins mounted on said anode and defining therebetween a plurality of parallel longitudinal cooling paths communicating with said anode, an envelope member surrounding said fins and secured to the edges thereof remote from the anode to close off the cooling paths, said envelope having a plurality of axially-spaced annular apertures therein enabling access to the cooling paths, and means for introducing a cooling medium through a plurality of said apertures into said cooling paths at axially-spaced positions and withdrawing said cooling medium from one extremity of said fins, whereby the flows of the cooling medium join along the cooling paths thereby increasing the velocity of the cooling medium.
